UNITED STATES PATENT OFFICE.

ALBERT FRANKLIN KUHL, OF VAN WERT, OHIO.

MAIL-RECEIVER.

No. 873,247.

Specification of Letters Patent.

Patented Dec. 10, 1907.

Application filed September 27, 1907. Serial No. 394,902.

To all whom it may concern:

Be it known that I, ALBERT FRANKLIN KUHL, a citizen of the United States, residing at Van Wert, in the county of Van Wert and State of Ohio, have invented a new and useful Mail-Receiver, of which the following is a specification.

This invention relates to mail bag catchers and has for its object to provide a basket or receptacle designed for erection at the several stations along the route and adapted to catch and hold the mail bags or sacks as the latter are discharged from a moving train.

A further object of the invention is to provide a standard having a basket carrying frame pivotally mounted for swinging movement thereon and capable of being swung laterally on either side of the standard so that the basket may be in position to receive the mail bags or sacks discharged from a train traveling in either direction.

A further object is to provide a basket or receptacle comprising pivotally united sections movable downwardly to open position, one of said sections forming a guard to prevent accidental displacement of the mail sack when the opposite section is open.

A further object is to provide means for locking the basket sections in open position, and means disposed between said sections and actuated by the impact of the mail bag for releasing the basket sections.

A still further object of the invention is to generally improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a side elevation of a mail bag catcher or receiver constructed in accordance with my invention. Fig. 2 is a sectional top plan view taken on the line 2--2 of Fig. 1.

Similar numerals of reference indicate corresponding parts in all of the figures of the drawings.

The improved mail bag catcher or receiver forming the subject matter of the present invention includes an oscillating basket supporting frame 5 pivotally mounted for swing-

ing movement on a standard or support 6, one of said standards or supports being preferably arranged at each station along the route. The frame 5 is substantially rectangular in shape, and provided with transverse bars 7 and 8 preferably reinforced and strengthened by diagonal braces 9 which connect the side walls of the frame with the transverse bars 7 and 8, as shown.

Mounted between the side bars of the frame 5 is a receptacle or basket adapted to receive the mail bags and preferably formed in two sections 10 and 11 movable laterally and downwardly to open position. The sections 10 and 11 may be formed of wood, metal or other suitable material but are preferably constructed of wire gauze and are each reinforced and strengthened by a rectangular frame 12, the adjacent ends of the wire forming the frames 12 being bent to produce co-incident eyes 13 which engage pivot rods or pins 14 extending transversely across the side bars of the frame 5. The frame sections 10 and 11 are further reinforced and strengthened by parallel braces 15 each having one end thereof pivotally connected with the adjacent rod 14 and its opposite end secured to a yoke 16 carried by the frame 12, there being diagonal brace wires or rods 17 extended across the bottom of each frame, as shown. Mounted on the rods 14 are coiled springs 18 which serve to normally and yieldably maintain the basket sections 10 and 11 in closed position.

Secured to the lower transverse bar 8 and preferably arranged at right angles to the standard or support 6 is a longitudinally disposed bar forming oppositely disposed arms 19 each provided with a depending flange or plate 20 adapted to bear against a leaf spring 21 secured to a longitudinal bar 22 mounted at the rear of the support or standard 6 and rigidly secured thereto.

Secured to the upper faces of the arms 19 are casings or housings 23 each having a catch 24 pivotally mounted therein with its lower end extended beneath the adjacent arm and pivotally connected through the medium of a rod 25 with a bell crank lever 26. The bell crank levers 26 are pivotally mounted at 27 in suitable hangers depending from the longitudinal bar 19 and are each provided with a relatively long arm 28, the free end of which is normally seated in a loop 29 of a trip rod 30.

The trip rod 30 extends upwardly through the lower transverse brace bar 8 with its upper end disposed between the rods 14, and pivotally connected with the upper or free end of the trip rod 30 is a plate or trigger 31 having its opposite ends provided with trunnions 32 which are journaled in the adjacent side bars of the basket supporting frame, as shown. The trigger 31 is actuated by the impact of the mail bag when the latter is thrown into the basket from a moving train thereby to elevate the rod 31 against the tension of the coiled spring 33 and thus release the catches 24 from engagement with the basket sections so that the springs 18 may automatically move said sections to closed position.

It will here be noted that the yokes 16 not only serve to reinforce and strengthen the basket frames but, by engagement with the hooked terminals of the catches 24 serve to hold the basket open and in position to receive the mail bags or sacks.

Pivottally connected with the bell crank levers 26 are locking rods 34 which project through suitable guides 35 carried by the adjacent arms 19 and are adapted to engage loops or eyes 36 secured to the adjacent ends of the longitudinal bar 22 thereby to lock the basket carrying frame on either side of the standard and in position to receive the mail when a train is traveling in either direction.

Extending transversely across the frame at the upper end thereof are spaced bars 37 which serve to receive the impact of the basket sections 10 and 11 when the latter are moved to closed position by the action of the coiled springs 18.

As a means for locking the basket sections in closed position so as to prevent an unauthorized person from attempting to operate the catcher, there is provided a locking member 38 consisting of a transverse rod provided with depending fingers 39 adapted to engage the basket sections at the rear of the frame 12, said locking member being movable to operative and inoperative position through the medium of a lever 40 having its intermediate portion pivotally mounted at 41 on a post carried by the upper transverse bar 7 and its outer end extended through a slot or opening 42 in the adjacent side bar of the basket supporting frame and provided with an eye 43 for pivotal engagement with an operating handle 44, there being a hasp or staple secured to the basket supporting frame at a point adjacent the operating handle 44 and adapted to receive a padlock or similar fastening device.

Arranged on each side of the standard 6 at a point sufficiently remote from said standards are posts 45 the upper ends of which are provided with laterally extending arms 46 adapted to receive and support a mail bag in the path of movement of a train so that the

mail from the several stations along the route may be delivered to the train without the necessity of stopping the latter.

Attention is here called to the fact that when one of the pivoted sections of the basket or receptacle is in open position the mating section thereof forms a guard or abutment so as to prevent the mail bags or sacks thrown into the basket from a passing train from being deposited on the platform at a station. It will also be noted that the basket supporting frame is free to swing laterally on either side of the support or standard 6 so that the basket sections 10 and 11 will be in convenient position to receive the mail sacks from a train traveling in either direction.

Should it be desired to receive mail from a train traveling in the direction of the arrow indicated in Fig. 2 of the drawings the basket section 10 is swung downwardly until the yoke 16 of said basket section catches the hooked terminal of the adjacent catch 24 and in which position said basket section will be locked against closing movement. The frame carrying the basket sections is then swung laterally on its pivotal points until the terminal of the locking rod 34 engages the adjacent loop or eye 36 and in which position the basket carrying frame may be rigidly combined with the longitudinal bar 22 with the basket section 10 arranged in convenient position to receive the mail discharged from the train, as best shown in Fig. 2 of the drawing. As the mail bag is discharged into the receptacle said mail bag will strike the plate or trigger 31 and tilt the same in the direction of the section 11 thus causing the trigger to exert an upward pull on the trip rod 30 and through the medium of the bell crank levers and connecting rods 25 trip the catches 24 so that the coiled spring 18 is free to move the section 10 to closed position. When the bell crank levers 26 are actuated by the trigger 31 the rods 34 will be withdrawn from the keepers or eyes 36, the springs 21 at the same time forcing the basket carrying frame laterally to a position substantially parallel with the longitudinal bar 22. It will thus be seen that the basket carrying frame may be swung alternately on either side of the support or standard 6 while either basket section may be moved to open position according to the direction of travel of the train, the opposite or mating basket section at the same time serving as a guard to prevent accidental displacement of the mail bags.

In order to lock the basket sections in position preparatory to removing the mail from said basket suitable hooks 47 are pivotally mounted at 48 on the casings 23 and adapted to engage the adjacent edge of the basket sections so as to prevent the coiled springs from closing the sections and cutting 130:

or otherwise lacerating the hands of the operator.

In order to deliver the mail to a passing train it is merely necessary to suspend the mail bags or sacks from the terminals of the arms 46 when the fork on the mail car will engage and detach said mail bags in the usual manner.

From the foregoing description it is thought that the construction and operation of the device will be readily understood by those skilled in the art and further description thereof is deemed unnecessary.

Having thus described the invention what is claimed is:

1. A mail bag catcher including a support, a frame mounted for swinging movement on the support, a sectional basket carried by the frame, means for locking the basket sections in open position, and means operable by the impact of the bag for releasing the locking means.

2. A mail bag catcher including a support, a frame mounted for swinging movement on the support, a sectional basket carried by the frame, means for locking the basket sections in open position, means for locking the frame on either side of the support, and means disposed between said sections and operable by the impact of the bag for releasing the frame and basket locking means.

3. A mail bag catcher including a support, a frame pivotally mounted for swinging movement on the support, a sectional basket carried by the frame, means for locking the basket sections in open position, means for alternately locking the frame on each side of the support, and means operable by the impact of the bag for releasing the frame and basket locking means.

4. A mail bag catcher including a support, a frame pivotally mounted for swinging movement on the support, a sectional basket carried by the frame, means for locking the basket sections in open position, means for alternately locking the frame on each side of the support, and means disposed between the basket sections and operatively connected with the frame and basket locking means for releasing the same.

5. A mail bag catcher including a support, a frame pivotally mounted for swinging movement on the support, a basket carried by the frame and comprising mating sections one of which forms a guard when the other is in open position, means for locking one of said sections in open position, and means operable by the impact of the mail bag for releasing the locking means.

6. A mail bag catcher including a support, a frame pivotally mounted for swinging movement on the support, a basket carried by the frame and formed of pivotally united sections one of which forms a guard when the other is in open position, a spring for auto-

matically moving the sections to closed position, means for alternately locking the frame on each side of the support, means for locking the basket sections in open position, and a trigger operatively connected with the frame and basket locking means for releasing the same.

7. A mail bag catcher including a support, a frame mounted for swinging movement on the support, a sectional basket carried by the frame, means for locking the basket sections in open position, means for locking the frame alternately on either side of the support, a plate pivotally mounted on the basket carrying frame between said sections and operatively connected with the basket and frame locking means, said plate being operable by the impact of the bag for automatically releasing the frame and basket sections.

8. A mail bag catcher including a support, a frame mounted for swinging movement on the support, a sectional basket carried by the frame, means for locking the basket sections in open position, means for locking the frame alternately on each side of the support, and means for simultaneously releasing the basket and frame locking means.

9. A mail bag catcher including a support, a frame mounted for swinging movement on the support, a sectional basket carried by the frame, means for locking the basket sections in open position, means for locking the frame on either side of the support, means disposed between the basket sections and operatively connected with the frame and basket locking means for releasing the same, and yieldable means for oscillating the basket carrying frame when the frame locking means is released.

10. A mail bag catcher including a support, a frame mounted for swinging movement on the support, a sectional basket carried by the frame, arms secured to the frame, casings extending vertically from the arms, locking members mounted in the casings and adapted to engage the basket sections for locking the same in open position, and means operable by the impact of the mail bag and operatively connected with the locking members for automatically releasing the same.

11. A mail bag catcher including a support, a frame mounted for swinging movement on the support, a sectional basket carried by the frame, arms extending laterally from the frame, casings secured to the arms, locking members pivotally mounted in the casings and adapted to alternately engage the basket sections, a trigger disposed between said sections, and a rod depending from the trigger and operatively connected with the locking members for releasing the basket sections, said trigger being operable by the impact of the mail bag.

12. A mail bag catcher including a support, a frame pivotally mounted for swinging

movement on the support, a sectional basket carried by the frame, arms secured to the frame, casings carried by the arms, locking members pivotally mounted on the casings and adapted to engage the basket sections for holding the same in open position, a trigger disposed between said sections, bell crank levers secured to the arms, links forming a pivotal connection between the locking members and bell crank levers, and a spring actuated trip rod forming a pivotal connection between the bell crank levers and trigger, said trigger being actuated by the impact of the bag for releasing the locking members thereby to automatically close the basket sections.

13. A mail bag catcher including a support, a frame mounted for swinging movement on the support, a sectional basket carried by the frame, locking members disposed on each side of the basket, bell crank levers pivotally mounted on the swinging frame, links forming a pivotal connection between the bell crank levers and locking members, a bar secured to the support and provided with keepers, longitudinally movable locking rods pivoted to the bell crank levers and adapted to engage the keepers for locking the swinging frame on either side of the support, and means operatively connected with

the bell crank levers and actuated by the impact of the mail bag for simultaneously releasing the locking members and rods, respectively.

14. A mail bag catcher including a support, a frame mounted for swinging movement on the support, a sectional basket carried by the frame, locking members pivotally mounted on each side of the basket and adapted to alternately engage the sections for locking the same in open position, a longitudinal bar secured to the support and provided with keepers, locking rods slidably mounted on the frame and adapted to engage the keepers for alternately locking the frame on either side of the support, a trigger operatively connected with the locking members and rods and operable by the impact of the mail bag for simultaneously releasing said rods and locking members, means independent of the locking means for supporting the sections in open position, and means for locking the basket sections in closed position.

In testimony that I claim the foregoing as my own, I have hereto affixed my signature in the presence of two witnesses.

ALBERT FRANKLIN KUHL.
